UNITED STATES PATENT OFFICE.

JAMES GANNON, OF BRISTOL, VIRGINIA, ASSIGNOR TO THE NATIONAL PNEUMATIC PUMP AND MANUFACTURING COMPANY, OF TENNESSEE.

PUMPING MECHANISM.

SPECIFICATION forming part of Letters Patent No. 666,803, dated January 29, 1901.

Application filed June 16, 1899. Renewed October 6, 1900. Serial No. 32,286. (No model.)

To all whom it may concern:

Be it known that I, JAMES GANNON, a citizen of the United States, residing at Bristol, in the county of Washington and State of Virginia, have invented new and useful Pumping Mechanism, of which the following is a specification.

This invention relates to pumping mechanism, and more particularly to that class in which a vessel is submerged at the bottom of a well and is adapted to receive water, which is then forced therefrom and out of the well by air-pressure, the vessel comprising two separate chambers which are adapted to be alternately filled and exhausted.

The object of the invention is to provide a simple and efficient mechanism through the medium of which a continuous flow of water may be secured and in which, moreover, the air is exhausted through the same opening through which it enters, thus enabling the water-inlet valve to operate with the greatest efficiency.

In the drawings forming a portion of this specification, and in which like numerals of reference designate corresponding parts in the several views, Figure 1 is a central longitudinal section of the submerged vessel and the supply-pipe with its valves, also of the delivery-pipe, other parts being in elevation. Fig. 2 is a transverse section taken through the submerged vessel at the left of the valve mechanism and showing all parts, with the section of the outlet-valves, in elevation. Fig. 3 is a detail section of a portion of the end of the vessel with its inlet-valve. Fig. 4 is a detail elevation of the air-inlet pipe with the regulating-valve thereon.

Referring now to the drawings, 5 represents a vessel comprising two equal chambers 6 and 7, separated by a partition 8 transversely of the vessel, which latter is preferably of a cylindrical form. This vessel 5 is adapted to rock in a plane including its axis, the rocking arrangement of said vessel being secured through the medium of pipe connections, including nipples 10 and 11, rockingly mounted in stuffing-boxes in the ends of the stems of T-pipe connections 12 and 13, with which are connected pipes 14 and 15, the former of which affords a means of supplying air to the cham-

bers 6 and 7 successively, while pipe 15 receives and conveys water from the vessels upwardly and out of the well. Connected also with the T connections 12 and 13 are pipe-sections 16 and 17, which extend downwardly and are seated in sockets 18 and 19, formed upon a connecting-beam 20 and acting as a support therefor. The pipes 14 and 15 above the vessel 5 comprise T connections 21 and 22, the stems of which are connected by a brace-pipe 23, adapted to stiffen the structure, and which is stopped intermediate its ends, so that there may be no connection between pipes 14 and 15 therethrough.

The nipple 11 is formed upon the barrel 25 of a valve, having an inlet-opening 26 intermediate its ends, and through which opening the nipple 11 communicates with the barrel 25. Equidistant from and on opposite sides of the opening 26 and in the opposite wall therefrom are formed two outlets or openings 27 and 28, of which the opening 27 communicates with the bore of a tubular extension 29, which is continued through the wall of the chamber 6 and has connected therewith an inwardly and upwardly extending pipe 30, which terminates in the upper portion of the chamber adjacent the partition 8. Intermediate the opening 27 and the adjacent end 80 of the barrel 25 is an opening 31 (shown in dotted lines in Fig. 1 of the drawings) and which communicates with a tubular outlet 32.

A tubular extension 35, communicating with the opening 28 in the barrel of the pump, 85 projects into the chamber 7 of the vessel and has connected therewith a pipe 36, which extends inwardly and upwardly and parallel with the pipe 30 and terminates adjacent the upper wall of the vessel and the partition 8. 90 An outlet-opening 37 is formed in the upper wall of the barrel 25 intermediate the opening 28 and the adjacent end of the barrel, as shown in dotted lines in Fig. 1, which opening communicates with a tubular extension 95 38, as shown in Fig. 4.

A removable plug is fitted in one end of the barrel 25, while in the other end is arranged a stuffing-box 39, through which is passed a valve-rod 40, having arranged thereon, within the barrel, two pistons 41 and 42, so positioned that when piston 42 is between

the opening 27 and the adjacent end of the barrel the piston 41 will lie intermediate the openings 28 and 26, so that any air that may be forced through pipe 14 may pass through 5 the nipple 11 and into the valve-barrel and thence through the opening 27 into the extension 29 and pipe 30 into the chamber 6. At the same time the chamber 7 will have a direct communication with the exterior of 10 the vessel through the pipe 36, the extension 35, the opening 28, the barrel, the opening 37, and extension 38. When the valve-rod is moved to its opposite position, the flow of air from pipe 14 inwardly will be through 15 pipe 36 to the chamber 7, while chamber 6 will communicate with the exterior of the vessel through the valve-barrel and the extension 32. In order to effect this shifting of the valve-rod and the pistons carried thereby, I 20 secure to the barrel 25 ears 45, between which is pivoted an L-shaped lever 46, one end of which is slidably connected with the valve-rod, while the other end thereof is extended through a keeper 47, carried by the pipe 17. 25 Thus it will be seen that as the vessel 5 is rocked the connection of the lever 46 with pipe 17 will cause an alternate shifting of the valve mechanism from one position to the other. In order to cause this rocking of the 30 vessel 5 and at the same time to cause the chambers 6 and 7 to alternately fill with water, I form an opening in the outer end of each chamber 6 and 7 and adjacent the upper wall thereof, each of which openings has an 35 inwardly-opening valve 48, as shown in Fig. 3 of the drawings, so positioned that when the vessel is tilted the uppermost valve will hang open, while the lowermost valve will be closed by gravity. Guard-netting 49 is secured over the outer ends of the openings just described to prevent ingress of gravel and other objectionable matter.

In order to allow the flow of water from the chambers 6 and 7 at the time air is being 40 forced thereinto, I arrange at each side of the partition 8 an outlet-pipe 50 and 51, which pipes are extended upwardly and outwardly and are connected with the extensions 52 and 53, which enter the wall of the 45 vessel 5 at each side of the partition 8 and which are formed upon the casings of outwardly-opening check-valves 54 and 55 in the legs of a U-shaped connection upon which the nipple 10 is formed. Thus it will be seen 50 that if the apparatus be placed in a well with the vessel 5 submerged and one of the chambers be allowed to fill with water it will immediately sink, shifting the pistons 41 and 42 to a position which will open the sunken 55 chamber to the air-inlet pipes, and thus if air-pressure be contributed to the pipe 14 the water will be forced out of the sunken chamber and through its respective pipes 50 or 51 and pipe 15 and thence upwardly and out of 60 the well. At this time the valve 48 in the uppermost chamber is open and water is run-

ning into it. This filling of the uppermost chamber will continue until such an amount of water has been exhausted from the sunken chamber as to allow it to be overbalanced by 70 the other chamber, when the vessel will rock to the other position and will shift the valve to its opposite position to allow the forcing of the water out of the last sunken chamber and to allow the passage of air out of the chamber 75 just cleared of the water to permit the passage of water thereinto. This operation will be continued so long as the supply of air be contributed through the pipe 14, the check-valves 54 and 55 preventing back pressure of 80 water from the chamber being cleared into the opposite chamber.

It will be seen from this description that by this intermittent and constant rocking of the vessel a continuous flow of water may be 85 secured, while the parts are in themselves so simple in construction and operation as to insure an efficient operation at all times.

It will be understood that the shape of the vessel may be varied as desired, that the 90 frame may be altered, that the general construction and arrangement may be varied without departing from the spirit of the invention, and that any desired means connected with the beam 20, such as a beam 60, having 95 upwardly-projecting stops at its ends, may be employed for limiting the rocking motion of the vessel.

Having thus described the invention, what is claimed is—

1. The combination with a supporting-frame comprising inlet and outlet pipes having openings therein, of a vessel comprising separate chambers, hollow trunnions for said vessel by which it is rockingly mounted in 105 communication with the openings of said pipes, a connection at each side of the separating-partition of said chambers leading to one of said trunnions and having a common outwardly-opening valve, a valve-barrel carried by the opposite trunnion and having openings communicating with the chambers, said barrel communicating also with its trunnion, air-outlet openings in said barrel, and means for alternately opening and closing said 115 first-named openings with respect to the inlet-pipe and for alternately opening and closing the air-outlet openings in the barrel with respect to the openings that communicate with the chamber.

2. The combination with a supporting-frame comprising inlet and outlet pipes having openings therein, of a vessel comprising separate chambers, hollow trunnions for said vessel by which it is rockingly mounted in 125 communication with the openings of said pipes, a valved connection between the bottom of each chamber and the outlet-trunnion, a valve-barrel carried by the trunnion connected with the inlet-pipe, and having communication therewith, inlet-openings in the valve-barrel having communication with the

upper portions of their respective chambers, air-outlet openings in said barrel, pistons adapted to alternately open each of said inlet-openings through the barrel to the adjacent trunnion and for opening said inlet-openings alternately through the barrel to the air-outlet openings of the latter.

In testimony that I claim the foregoing as my own I have hereto affixed my signature in the presence of two witnesses.

JAMES GANNON.
